UNITED STATES PATENT OFFICE.

HERMAN BIEDER, OF ASHTABULA, OHIO.

APPARATUS FOR MANUFACTURING ICE-CREAM.

SPECIFICATION forming part of Letters Patent No. 651,411, dated June 12, 1900.

Application filed July 12, 1899. Serial No. 723,528. (No model.)

To all whom it may concern:

Be it known that I, HERMAN BIEDER, a citizen of the United States, and a resident of Ashtabula, county of Ashtabula, and State of Ohio, have invented a new and useful Apparatus for Manufacturing Ice-Cream, of which the following is a specification, the principle of the invention being herein explained and the best mode in which I have contemplated applying that principle so as to distinguish it from other inventions.

My invention relates to an improved apparatus for treating ice-cream for the purpose of imparting to it greater smoothness and homogeneity than has heretofore been obtained.

My improved process consists in expanding the air or other gases which may be contained in the pores of the mixture, the method of and apparatus for carrying out said process being hereinafter fully described.

The annexed drawings and the following description set forth in detail one mode of carrying out the invention, such disclosed mode constituting but one of various ways in which the principle of the invention may be used.

In said annexed drawings, Figure I represents a longitudinal axial section of the freezer-can, the receptacle for containing the freezing mixture, and the dasher, the machine-frame and other parts being shown in elevation. Fig. II represents a front elevation of the freezing-mixture receptacle with a section removed, showing the freezing-can in elevation therein. Fig. III represents a vertical central cross-section of the apparatus. Fig. IV represents a detail view, and Fig. V a vertical central cross-section, looking toward the right of Fig. I; and Fig. VI an end elevation of the freezer-can.

A cylindrical receptacle A has secured to one head a a shaft B, whose axis coincides with the receptacle-axis and which is mounted in a **U**-bearing B'. A suitable driving-pulley B² is secured to said shaft. In the middle of the opposite head a' is a bearing a^2 , in which is journaled the end of a shaft C, also mounted in a **U**-bearing and driven by a pulley C'. The two bearings c and c' of the **U**-bearing are placed at a distance from

each other such that said pulley C' and the shaft C may be longitudinally moved some distance, so that the shaft may be projected a short distance into the receptacle A, as shown in dotted lines, Fig. I. Within said receptacle A and coaxial therewith is located a cylindrical freezer-can D, whose head d rests upon lugs a^3 , Fig. V, placed at suitable intervals. The opposite head d' is made removable and secured to the can by means of pivotal bolts d^2 and cams d^3 , an elastic washer d^4 being interposed to form an air-tight joint. Through the center of said removable head is formed a taper journal-bearing d^5 , through which extends and bears a taper journal e , formed on the end of the spindle of the dasher E, Fig. I. The opposite end of said spindle is tapered and bears in a taper bearing d^6 , formed upon the inside of head d of the freezer-can, as shown.

The outer extremity of the taper journal e is secured, fits into, and rotatively engages the inner end of the shaft C, said shaft end being formed as shown in Fig. IV, the construction being such that the square spindle end may be placed in the slot c^2 , the shaft moved into the receptacle A, and said spindle end thereby caused to interiorly engage a square seat c^3 , formed in continuation of the said slot, the arrangement thereby permitting the freezer-can to be removed and replaced with facility.

A longitudinal section A' of the receptacle A is made removable, Fig. III, secured by suitable means, and is of sufficient width to form on removal an opening large enough to permit of the passage of the can D. In the head d' of said can is formed an opening which communicates with a pipe F, which connects said opening with an opening in the receptacle A, as shown in Figs. I and II. A check-valve f , Fig. VI, is located in said pipe and opens inwardly. The outer end of said pipe is suitably formed or provided with means for making an air-tight connection with a pipe or duct G, which communicates with any suitable source of air under pressure.

I carry out my process and operate the above-described device as follows: The freezing-can having been removed from the recep-

tacle A and the head d' removed, the ice-cream mixture is poured into same and the said head replaced, thus sealing the freezer and confining the mixture in an air-tight space. The 5 can is then replaced, the dasher caused to operatively engage the shaft C, as before described, the freezing mixture placed in the receptacle A around the can, the cover A' secured in place, and the said receptacle and 10 the dasher rotated in opposite directions by means of the driving-pulleys, the can D rotating with the receptacle. After the mixture has congealed to a predetermined degree the rotation is stopped and the end of the 15 pipe F connected with the compressed-air supply, such compressed air being thus injected into the ice-cream mixture and the internal pressure of the air or gases in the pores of the mixture raised above the pressure of 20 the surrounding atmosphere. The efflux of air from the can is prevented by the check-valve, so that the imparted pressure is maintained as desired. On completion of the freezing process the can is removed from the receptacle A and the head d' removed. On 25 such removal the confined gas immediately expands throughout the frozen mixture, causing it to expand to greater volume and imparting to it a homogeneity and smoothness 30 desired in ice-cream.

Other modes of applying the principle of my invention may be employed instead of the one explained, change being made as regards the mechanism herein disclosed, provided the 35 means covered by any one of the following claims be employed.

I therefore particularly point out and distinctly claim as my invention—

1. The combination of a can, congealing means, a source of gas under pressure, said can having communication with said source and excluded from communication with the atmosphere, substantially as set forth.

2. The combination of a sealed can, congealing means, a source of gas under pressure, means for connecting said can and said source of pressure whereby such gas is permitted to enter and is retained in said can, substantially as set forth.

3. A freezing-can having a removable cover 50 adapted to render the can air-tight, and having an air-inlet controlled by a valve adapted to prohibit atmospheric communication with the interior of said can, substantially as set forth.

4. The combination of a receptacle for containing freezing mixture, a freezing-can supported in and removable from said receptacle, the latter provided with an aperture having a removable cover for permitting said can to be inserted or removed from said receptacle, and an air-duct connecting the interior of said can with the exterior of the receptacle, said duct provided with a valve adapted to prohibit atmospheric communication with said interior, substantially as set forth.

Signed by me this 26th day of June, 1899.
HERMAN BIEDER.
